HUGO ENDERS, OF BELLEVILLE, NEW JERSEY, ASSIGNOR, BY MESNE ASSIGNMENTS, TO THE LEHIGH CORPORATION, OF NEW YORK, N. Y., A CORPORATION OF DELAWARE.

CALCULATING MACHINE.

1,414,729.

Specification of Letters Patent.

Patented May 2, 1922.

Application filed October 29, 1919, Serial No. 334,113. Renewed March 25, 1922. Serial No. 546,890.

To all whom it may concern:

Be it known that I, HUGO ENDERS, a citizen of the Republic of Germany, and a resident of Belleville, in the county of Essex and State of New Jersey, have invented certain new and useful Improvements in Calculating Machines, of which the following is a specification.

This invention relates to calculating machines of that type in which a plurality of calculating disks are fixed upon a common shaft, each disk being equipped with a plurality of radially movable pins or teeth to coact with a series of results registering numeral wheels, and having means for adjusting said pins.

The main object of my present invention is to provide a manually operable member or handle for the tooth adjusting means carried by each disk, and provide means for automatically connecting the adjusting means to said handle when the operating crank is in its zero position and which is automatically disconnected from the handle 15 and shifted to engage the tooth adjusting means with its corresponding calculating disk when the operating crank handle is released from its zero position to permit it to be rotated to effect the rotation of the calculating disks. The invention also comprehends the provision of simple and effective means for setting up the calculated numbers upon a separate series of numeral wheels, a master key for resetting said numeral wheels to zero, and additional keys for individually resetting said numeral wheels.

It is a further general object of my invention to provide a calculating machine 20 having the improved features above referred to, which is simple in its construction, accurate and reliable in operation and not liable to get out of order.

With the above and other objects in view, the invention consists in an improved calculating mechanism as characterized, and in the construction, combination and relative arrangement of its several elements as will be hereinafter more fully described, illustrated in the accompanying drawings, and subsequently incorporated in the subjoined claims.

In the drawings wherein I have illustrated one practical embodiment of my invention, and in which similar reference

characters designate corresponding parts throughout the several views.

Fig. 1 is a longitudinal section, a portion of the casing being shown in elevation, illustrating the normal relative positions of the parts when the operating handle is locked against movement;

Fig. 2 is a sectional plan view of the mechanism;

Fig. 3 is a transverse section taken on the line 3—3 of Fig. 1;

Fig. 4 is an enlarged detail vertical section through one of the calculating disks showing the tooth adjusting means carried by said disk operatively connected to the manually shiftable actuating means therefor;

Fig. 5 is a transverse section showing the operating means for the rectilinearly movable plate which releases the tooth adjusting means from the calculating disk; and

Fig. 6 is a detail plan view of said plate.

Referring in detail to the drawings, 5 designates a suitable case or housing which is fixed upon a bed plate and transverse frame members as is usual in the construction of such machines. In spaced frame members 5' of the machine, a shaft 7 is journaled at its ends. Upon this shaft a series of spaced calculating disks 6 are keyed or otherwise rigidly fixed. Each of these disks carries a series of radially movable pins or teeth 8, there being nine teeth in each series. These radial teeth are adjusted and projected beyond the peripheral face of the disk 6 at their outer ends by means of a cam disk 9, which is loosely mounted to rotate upon a hub portion 10 formed on one side of the disk 6. This cam disk is provided with a cam slot 11 and each of the pins 8 is formed with a lug 12 projecting from one side thereof and into said cam slot.

Each disk 6 is provided with a circumferential groove 13 to receive the inwardly bent terminals of the fingers 14 which are securely fixed to the marginal edge of the cam disk 9. A screw 15 extends through the cam slot 11 and is threaded in the disk 6. This screw and the fingers 14 serve to retain the cam disk 9 against the face of the disk.

To each of the adjustable cam disks 9, a leaf spring 16 is securely fixed at its inner end by means of screws 17. This spring extends radially beyond the periphery of the disk and through a slot 19 in the curved

metal plate 18 which extends longitudinally over the series of calculating disks between the same and the front wall of the case or housing 5. It will be understood that a 5 separate slot 19 is provided in this plate for each of the leaf springs 16. The plate 18 is further provided at its opposite ends with the slots 18' to receive suitable guide bolts fixed in the frame of the machine.

10 The front curved wall of the casing 5 is likewise provided with slots 20 therein, corresponding in number and location with the slots 19 in the plate 18. In each slot 20 a longitudinal movable handle slide 21 is engaged, the part of said handle slide extending through the slot being relatively narrow and said handle slide having a head 22 on its inner end movable between the wall of the case or housing and the plate 18. This head 15 on one side is provided with a recess 22' adapted to receive the outer end of the leaf spring 16 when said spring is flexed in the manner to be presently described. A fixed pin 23 projects from one side of the leaf 20 spring and is adapted for engagement through an opening in the adjustable plate 9 and in any one of a plurality of sockets 24 in the face of the disk 6. In this normal position of the leaf spring and the pin 23, that 25 is, the position in which the spring is unflexed and in its normal condition, it will be seen that the plate 9 is locked to the disk 6 for rotation as a unit therewith.

A series of independently rotatable result 30 registering numeral wheels 25 are mounted upon a common shaft 26 extending longitudinally in the front lower portion of the case 5, and suitably fixed at its ends in the frame members of the machine. The numerals on the peripheral faces of these 35 wheels are visible through openings 27 in the wall of the case, and each wheel is provided upon one side with cog teeth 28. With these teeth a series of independently 40 rotatable cog wheels 29 are respectively engaged, said wheels being mounted upon the common shaft 30. These cogs 29 are respectively engaged by the adjustable pins or teeth 8 carried by the disks 6 and in turn 45 transmit rotation to the numeral wheels 25, the extent of such rotation of course, depending upon the number of the pins or teeth 8 which have been projected from the periphery of the disks 6 in position for 50 engagement with the teeth of the cogs 29.

Any suitable transfer mechanism between 55 the totalizing wheels 25 whereby upon a complete revolution of any one wheel, or as illustrated a half revolution of any one 60 wheel, a one step movement may be transmitted to the next succeeding wheel, may be used. A large number of different mechanisms to this end are well known in the art and I do not wish to be limited to any particular means for this purpose, nor have I

illustrated any particular means to this end, as the transfer mechanism between the totalizing wheels has nothing whatever to do with my present invention. A transfer mechanism, which is adapted to be used with 70 a calculating machine of this character, is illustrated in Patent 957,062, granted to Erwin Jahnz on the 3rd day of May, 1910.

In addition to the series of result registering numeral wheels, I also provide a second 75 series of numeral wheels 31 mounted in the case above and rearwardly of the series of calculating disks, the numerals being visible through openings 32 in the wall of the case, for the purpose of setting up the number 80 being calculated so that it may remain visible during the operation of the machine. Each of these latter numeral wheels is also provided with cog teeth 32' on one side to mesh with the teeth of a series of independently 85 rotatable cog wheels 33 which are mounted upon the fixed shaft 34. A pawl 35 is provided for each of these cog wheels, said pawl being of substantially U-shaped form and pivoted as at 36 upon a fixed part 90 of the machine frame. One end of each pawl is V-shaped as at 37 for engagement between the teeth of a corresponding cog wheel 33 to hold said wheel against rotation under the action of a spring 38, which at one of its 95 ends is fixed to the hub 33' of the cog wheel and at its other end is connected to the opposite end of the pawl 35 which extends upwardly and is angularly offset as at 39. As the wheel 33 is revolved, it acts to wind the 100 spring 38 around the hub 33' so that the spring 38 exerts a tension acting to rotate the corresponding wheel 33.

The opposite longitudinal edges of the plate 18 are angularly offset or flanged as at 105 40, and the upper end of each slot 19 extending into this flanged edge of the plate is widened as at 41 to permit the passage of an arcuate rack 42 curved in concentric relation to the disks 6. This rack at one of its 110 ends is fixed to the head 22 of the manually operable handle slide 21 and is supported and guided in its movement by means of a fixed metal bar 43 which holds the teeth of each rack in meshing engagement with the 115 teeth of the corresponding cog wheel 33. It will thus be evident that when the handle 21 is shifted, rotation is transmitted to the cog wheel 33 through the medium of the rack 42, which in turn transmits a rotative movement to the numeral wheel 31, the teeth 32' of which are operatively engaged with said cog wheel. In this rotation of the cog wheel, the spring 38 is wound at one of its ends upon the hub 33 of said wheel and is placed 125 under tension to urge the end 37 of the pawl 35 in effective engagement with the teeth of the cog wheel whereby the latter is held against a casual movement and the numeral wheel is retained in its set position. It will 130

be understood that the number on said wheel which is visible in the opening in the case wall corresponds to the number of the movable pins or teeth which are projected from the periphery of the disks 6 in the adjustment of the cam plate 9.

The operating shaft 44 is journaled in one end of the machine frame and is supported by a bracket 45. A gear 46 is fixed upon the inner end of this shaft and meshes with a gear 47 secured upon the rotatable shaft 7. At its outer end, the operating shaft 44 is provided with a crank handle 48. An axially movable rod 49 extends longitudinally within the machine case and at one of its ends is movable in a guide 50 formed on the bracket 45. At its other end, this rod is operatively connected by means of a pivoted link 51 to the lower end of a yoke member 52 which is fulcrumed as at 53 upon a fixed part of the machine frame. The arms of this yoke member are respectively pivoted to bifurcated lugs 54 fixed to the inner faces of the flanged edges 40 of the plate 18. The crank handle 48 carries a bolt 55 which is adapted to enter the bore of the guide lug 50 and is urged outwardly by a strong spring 56 arranged within said handle. The leaf springs 16 which extend through the slots 19 in the plate 18, urge the plate toward the right in Figure 1, and therefore these springs 16, through the medium of the plate 18 and the yoke 52 and the link 51 urge the rod 49 toward the right in Figure 1. This movement, however, is opposed by the relatively strong spring 56 which projects the bolt 55 against the end of the rod 49 and shifts said rod to the left in Figure 1 to thereby flex the leaf springs 16 and move the free ends of said springs relative to the cam disks 9 so that the outer ends of the springs are engaged in the recesses 22' of the slide members 21 while the pins 23 carried by said springs are disengaged from the sockets 24 in the disks 6. Thus, it will be seen that when the crank handle 48 is locked against rotation by the projection of the bolt 55 into the bore of the guide 50, the cam disks 9 are all released from their positive connection with the disks 6 so that said cam disks can be rotated with respect thereto. This rotation is effected through a shifting movement of the slides 21 whereby the teeth or fingers 8 are projected in accordance with the particular number being calculated, which may be observed upon the numeral wheels 31 which are simultaneously set in position in the manner above explained.

After all of the digits in the number being calculated have thus been set up upon the numeral wheels 31, the bolt 55 is disengaged from the guide lug 50 so as to release the crank handle 48. Simultaneously with this retraction of the locking bolt, the leaf springs 16 will return to their normal posi-

tions and thereby disconnect the adjustable cam disks 9, and consequently the calculating disks from the handle slides 21. The crank 48 is then rotated to transmit rotation to the series of calculating disks 70 through the medium of the shaft 44 and the projected pins coacting with the cog wheels 29 transmit rotation to the series of result registering numeral wheels 25. When one complete rotation of the crank handle is made, it is again locked against movement and the leaf springs 16 are returned to their former positions in operative connection with the handle slides 21. These handle slides are positively held against shifting movement during the operation of the calculating disks by means of the pawls 35 which are held by the springs 38 in engagement with the cog wheels 33. Thus the return of the leaf springs 16 to proper position for engagement in the recesses of the handle slides 22 upon the completion of one rotation of the calculating disks, is assured. The handle slides may then be adjusted to actuate the cam disks 9 and set up another number to be calculated, which, upon the next rotation of the series of calculating disks will be added to the number previously transmitted to the numeral wheels 25.

The numeral wheels 31 for indicating the number being calculated may all be reset at the same time by the operation of a master key 57 which at its lower end, is engaged with a longitudinally extending bar 58 resting upon the transversely disposed portions 100 of the U-shaped pawls 35. This key is normally urged upwardly by means of the spring 59. Individual keys 60 are also provided and at their lower ends are engaged with the respective pawls 35 to singly operate said pawls and thus individually reset the numeral wheels 31. Depression of these keys 60 is also resisted by means of springs 61. It will be understood, that immediately upon the disengagement of the ends 37 of the pawls from the teeth of the cog wheels 33, the springs 38 will act to rotate said cog wheels in a direction reverse to the direction of rotation transmitted through the medium of the racks 42, and thereby return the numeral wheels to zero position.

From the foregoing description considered in connection with the accompanying drawings, the construction, manner of operation and several advantages of my improved calculating mechanism will be fully understood. By means of a relatively simple arrangement of the elements, I have provided a calculating machine whereby numerous arithmetical computations may be rapidly and accurately performed. The adjusting means for the cam plates 9 permits of the rotation of said plates with the calculating disks, while the means for manually actuating the adjustable cam plates remains sta-

tionary. It will also be appreciated that the improved mechanism provides a very compact arrangement of the several mechanical elements and that such mechanism will be positive and reliable in its operation and not likely to easily get out of order.

While I have herein shown and described a preferred construction and relative arrangement of the several parts, it is nevertheless to be understood that the mechanism may also be exemplified in numerous other alternative combinations, and I accordingly reserve the privilege of adopting all such legitimate changes as may be fairly embodied within the spirit and scope of my invention as defined in the appended claims.

I claim:

1. In a calculating machine, the combination with a calculating disk having radially movable teeth and a rotative adjusting member for the teeth on the disk, of a manually shiftable handle for the adjusting member separate therefrom, means acting to yieldingly hold said handle in a zero position, means for operatively connecting the adjusting member to said handle and simultaneously disconnecting it from the calculating disk or disconnecting the adjusting member from the handle and simultaneously connecting it to the calculating disk, means acting to hold the handle in its manually shifted position, means for rotating the calculating disk and said adjusting member through a complete circle to thereby return the adjusting member into position to be engaged by said shiftable handle, means then acting to engage the adjusting member with the handle and disengage it from the disk, and manually operable means for releasing said handle holding means to permit the handle to return to its zero position.

2. In a calculating machine, the combination with a plurality of calculating disks, each having a series of radially movable teeth, and a tooth adjusting member for each disk, of a manually operable handle for each adjusting member separate therefrom, and means in one position locking the adjusting member to the disk for rotation as a unit therewith, said locking means being shiftable to a position to release the tooth adjusting member from its engagement with the disk and connect the tooth adjusting member to said handle for movement with the handle independently of the disk.

3. In a calculating machine, the combination with a series of calculating disks, each having a plurality of radially movable teeth and tooth adjusting means for each disk, of manually operable handles, one for each adjusting member, means in one position locking each adjusting member to its corresponding disk and in another position locking each adjusting member to its corre-

sponding handle, and a member common to all of said locking means shiftable in one direction to release the tooth adjusting means from engagement with the handles and simultaneously lock the tooth adjusting means to said disks and in the other direction to release the tooth adjusting means from said disks and connect them to the several handles.

4. In a calculating machine, the combination with a series of calculating disks, each having a plurality of radially movable teeth and tooth adjusting means for each disk, of manually operable handles, one for each adjusting member, means in one position locking each adjusting member to its corresponding disk and in another position locking each adjusting member to its corresponding handle, a member common to all of said locking means shiftable in one direction to release the tooth adjusting means from engagement with the handles and simultaneously lock the tooth adjusting means to said disk and in the other direction to release the tooth adjusting means from said disks and connect them to the several handles, an operating handle whereby the series of calculating disks may be rotated, and means controlled by the operating handle and acting when the handle is in zero position to shift said shiftable member into a position to release the tooth adjusting members from engagement with the disks and shift them into engagement with said handles.

5. In a calculating machine, calculating disks having radially movable teeth, an operating handle for rotating said disks and movable to or from a zero position, rotatable tooth adjusting cams coacting one with each disk, a series of handles, one for each tooth adjusting cam but separate therefrom, and means controlled by the operating handle and acting when the handle is at zero position to operatively disconnect the tooth adjusting disks from their corresponding calculating disks and connect the tooth adjusting disks to their respective handles and acting when the handle is shifted from a zero position to operatively connect the tooth adjusting disks to the calculating disks for rotation therewith and disconnect the tooth adjusting disks from said handles.

6. In a calculating machine, calculating disks having radially movable teeth, an operating handle for rotating said disks and movable to or from a zero position, manually operable means detachably locking the handle in a zero position, rotatable tooth adjusting cams coacting one with each disk, a series of handles, one for each tooth adjusting cam but separate therefrom, and means acting when the handle is locked in zero position to release the tooth adjusting cams from operative engagement with the corre-

sponding calculating disks and engage each tooth adjusting cam with its corresponding handle and acting upon an unlocking of the operating handle to lock the tooth adjusting cams to the calculating disks and release the tooth adjusting cams from operative engagement with their respective handles.

7. In a calculating machine, a calculating disk having radially movable teeth, a rotatable tooth adjusting cam coacting with the disk but independently movable with relation thereto, a handle separate from the tooth adjusting cam but coacting therewith, and means in one position locking the tooth adjusting cam to the calculating disk and releasing it from engagement with the handle and in another position locking the tooth adjusting cam to the handle but disengaging it from the disk.

8. In a calculating machine, the combination with a series of calculating disks each having a plurality of radially movable teeth and a tooth adjusting member for each of said calculating disks, of a leaf spring fixed to each of said members and having means to lock the adjusting member to the disk against movement with respect thereto, a manually operable handle for each of the adjusting members, and a common means coacting with the leaf springs to move the same into operative connection with the respective handles and release the adjusting members from locked connection with the disks whereby said members may be independently actuated to adjust the teeth of the calculating disks.

9. In a calculating machine, the combination with a series of calculating disks each having a plurality of radially movable teeth and an adjusting member for the teeth of each calculating disk, a leaf spring fixed to each of said members and having means to lock the adjusting member to the disk against movement with respect thereto, a manually operable handle for each of the adjusting members, a rectilinearly movable plate having spaced slots in which the respective leaf springs are engaged, and means for shifting said plate to flex the springs and operatively connect the same to the respective handles and release the adjusting members from locked connection with the calculating disks whereby said members may be actuated independently of the calculating disks to adjust the teeth of the calculating disks.

10. In a calculating machine, the combination with a series of calculating disks each having a plurality of radially movable teeth and teeth adjusting members, one for each of said calculating disks, a crank handle for the calculating disks, and means for locking the same in a zero position against movement, of means carried by each adjusting

member to engage the same to the corresponding disk, an actuator common to all of said engaging means, mechanism operatively connecting said actuator with the crank locking means whereby when the crank is locked, said disk engaging means are moved to release the adjusting members for movement relative to the calculating disks, and when the crank handle is released, said actuator is moved to engage the adjusting members to the disks, and a series of manually operable elements each one engaged by a corresponding disk engaging members when moved to its released position whereby the adjusting members may be independently actuated to adjust the teeth of the calculating disks.

11. In a calculating machine, the combination with a series of calculating disks each having a plurality of radially movable teeth and teeth adjusting members, one for each of said disks, a crank handle for the calculating disks, and means for locking the same against movement, of means carried by each adjusting member to engage the same to the disk for unitary movement, a common actuator for said engaging means, mechanism operatively connecting said actuator with the crank locking means whereby when the crank is locked, said engaging means are moved to release the adjusting members from engagement with the corresponding disks for independent movement, and when the handle is released, said actuator is moved to engage the adjusting members with the disks for unitary movement, a series of manually operable elements, each one engaged by one of the engaging means when moved to its released position whereby the adjusting members may be independently actuated to adjust the teeth of the calculating disks.

12. In a calculating machine, the combination with a series of calculating disks each having a plurality of radially movable teeth and a series of adjusting members for the teeth of each calculating disk, a crank handle for the calculating disks, and means for locking the same against movement, of means carried by each adjusting member to engage the same with the corresponding disk, a common actuator for said engaging means, mechanism operatively connecting said actuator with the crank locking means whereby when the crank is locked, said engaging means are moved to release the adjusting members for movement relative to the calculating disks, and when the handle is released, said actuator is moved to engage the adjusting members with the disks, a series of manually operable elements, each one engaged by one of the engaging means when

- moved to its released position whereby the adjusting members may be independently actuated to adjust the teeth of the calculating disks, a series of numeral wheels, mechanism operatively connecting said manually operable elements to the respective numeral wheels, a master key for resetting all of the numeral wheels to zero position, and additional keys for individually resetting said 10 numeral wheels to zero position.
13. In a calculating machine, the combination with a rotatable calculating disk having a plurality of adjustable teeth and an adjusting cam operatively engaging said 15 teeth and rotatable concentric to the disk, an operating handle mounted for movement concentric to the adjusting cam, and means for detachably connecting the tooth adjusting cam either to the calculating disk or to 20 the handle.
14. In a calculating machine, the combination with a calculating disk having a plurality of adjustable teeth, an adjusting cam operatively engaging said teeth and rotatable on the same axis as the calculating disk, an actuating handle movable concentrically to the actuating cam, means for connecting the tooth adjusting cam either to the calculating disk or to said handle, a numeral 25 wheel, and means for setting said numeral wheel in accordance with the movement of the tooth adjusting cam including an actuating member carried by said handle.
15. In a calculating machine, the combination with a calculating disk having a plurality of adjustable teeth, a tooth adjusting cam mounted for rotation upon the same axis as the disk, an actuating handle for the cam movable concentrically thereto, means 30 for detachably connecting the cam either to the calculating disk or to said handle, a numeral wheel, and means for shifting said numeral wheel in accordance with the movement of the cam including a gear wheel, and 35 an actuating rack engaged with said gear wheel and carried by said handle.
16. In a calculating machine, the combination with a calculating disk having a plurality of adjustable teeth, a tooth adjusting cam associated with the disk and rotatable upon the same axis, an actuating handle movable concentrically to the cam, means for detachably connecting the cam either to the disk for movement therewith or to the 40 handle for movement therewith and disconnecting it from the disk, a numeral wheel, means for shifting said numeral wheel in correspondence with the movement of the cam including a gear wheel and an actuating 45 rack engaged with said gear wheel and carried by said handle, and means for locking said gear wheel in its adjusted position against accidental movement when the cam has been operatively disconnected from the 50 handle and connected to the disk.
17. In a calculating machine, the combination with a series of calculating disks rotatable upon a common axis, each having a plurality of adjustable teeth, and a series of teeth adjusting cams, one for each calculating disk and rotatably mounted upon the same axis, a series of independently operable actuating handles for the series of cams, means for operatively connecting said cams to the corresponding disks and disconnecting them from the handles or connecting the cams to the handles and disconnecting them from the disks, calculating disk rotating means, and means controlling said connecting means operatively mounted upon the calculating disk rotating means. 75
18. In a calculating machine, the combination with a series of calculating disks, each having a plurality of adjustable teeth, a series of teeth adjusting cams, one for each of said disks and rotatably mounted concentrically to the several disks, of a series of independently operable handles for the series of cams, means for operatively engaging said cams with either their corresponding calculating disks or their corresponding handles, a series of numeral wheels, means for rotating said numeral wheels automatically operated by the actuation of said teeth adjusting cams when shifted to adjust the teeth of the respective calculating disks, and means for locking said numeral wheels against accidental movement when the cams are engaged with their respective calculating disks and rotatable therewith. 90
19. In a calculating machine, the combination with a series of calculating disks rotatable upon a common axis, each having a plurality of adjustable teeth, a series of teeth adjusting cams one for each calculating disk and rotatably mounted upon the same axis, a series of independently shiftable, manually operable actuating handles for the series of cams, means for each one of said handles urging it to a zero position, means for operatively connecting said cams to the corresponding disks and disconnecting them from the corresponding handles or connecting the cams to the handles and disconnecting them from the corresponding disks, calculating disk rotating means, means associated with each handle for locking it in its manually shifted position, and manually operable means for releasing the locking means to thereby permit the return of said handles to their zero position. 105
20. In a calculating machine, the combination with a series of calculating disks rotatable upon a common axis, each having a plurality of adjustable teeth, a series of teeth adjusting cams one for each calculating disk and rotatably mounted upon the same axis, a series of independently shiftable, manually operable actuating handles for the series of cams, means for each one of said handles 110
- 120
- 125
- 130

urging it to a zero position, means for operatively connecting said cams to the corresponding disks and disconnecting them from the corresponding handles or connecting the 5 cams to the handles and disconnecting them from the corresponding disks, calculating disk rotating means, means associated with each handle for locking it in its manually shifted position, manually operable means 10 associated with each locking means for releasing the individual locking means to permit the return of the individual handle to its zero position, and manually operable means for releasing simultaneously all of 15 said locking means to permit the simultaneous return of all of said locking handles to zero position.

21. In a calculating machine, a series of calculating disks, each having a plurality of 20 adjustable teeth, a series of cams for independently adjusting the teeth on each disk, a series of handles, one for each cam, means for operatively connecting each one of said cams to its appropriate handle and disconnecting it from the associated calculating disc or disconnecting the cam from the handle and connecting it to the associated calculating disc, said handles being manually shiftable to adjust the cams, manually 25 operable means for rotating the cams and calculating disks, an arcuate rack operatively carried by each of said handles and adjustable therewith as the handle is shifted, a spring acting to return each one of said 30 handles to its zero position, a series of pawls associated one with each of said racks permitting the manual shifting of the handles but holding the handles against accidental shifting movement, and means for manually 35 releasing each pawl to permit the return of its corresponding handle or manually releasing all of said pawls to permit the return of all of said handles to zero position.

22. In a calculating machine, a series of 40 calculating disks, each having a plurality of adjustable teeth, a series of cams for independently adjusting the teeth on each disk, a series of handles, one for each cam, means for operatively connecting each one of said 45 cams to its appropriate handle and disconnecting it from the associated calculating disc or disconnecting the cam from the handle and connecting it to the associated calculating disc, said handle being manually shiftable to adjust the cams, manually 50 operable means for rotating the cams and calculating disks, an arcuate rack operatively carried by each of said handles and adjustable therewith as the handle is shifted, a spring acting to return each one of 55 said handles to its zero position, a series of gear wheels associated one with each rack and engaging the same, a series of pawls, one for each gear wheel, permitting the rotation of the gear wheel upon the manual 60

actuation of the handle but holding the gear wheel, rack and handle from accidental shifting movement, and manually operable means for releasing any one of said pawls or all of said pawls.

70

23. In a calculating machine, a series of calculating disks, each having a plurality of adjustable teeth, means for independently adjusting the teeth on each disk and including a manually shiftable handle associated 75 with each disk and having an arcuate rack extending therefrom, a series of gear wheels, one for each rack, and engaging therewith, a series of pawls each engaging one of said gear wheels, each pawl being pivoted between its ends and having an upwardly extending tail, a coiled spring connected to the tail of each pawl and to the hub of the corresponding gear wheel whereby upon a rotation of the gear wheel in one direction 80 the spring will be wound upon the hub and placed under tension, means for manually shifting all of said pawls from their gear wheel engaging positions, and means for shifting any one of said pawls out of its 85 gear wheel engaging position to thereby permit the return of all of said handles to their zero position or the return of any individual handle to zero position.

90

24. In a calculating machine, the combination with a series of calculating disks, each having a plurality of radially movable teeth and a series of adjusting cams, each associated with one of said disks, of a series of manually operable handles for each of the 95 adjusting members, a leaf spring fixed to each of said adjusting cams and having means to engage the adjusting cam with the corresponding disk for common movement, said springs when flexed disengaging the 100 cam from the calculating disk and operatively engaging the corresponding handle, a rectilinearly movable plate having spaced slots in which the respective leaf springs are engaged, an operating crank handle for the 105 disks and having a spring pressed bolt resiliently projected when the crank handle and the calculating disks are in their zero positions, a longitudinally extending reciprocatable rod engaged and shifted in one direction by said bolt when the crank handle is in its zero position, and operative connections between said shiftable rod and said plate to cause the flexing of said leaf springs and their engagement with the handles when 110 said rod is shifted in one direction by engagement of the bolt with the rod.

115

25. In a calculating machine, the combination with a series of calculating disks, each having a plurality of radially movable teeth 125 and a series of adjusting cams, each associated with one of said disks, of a series of manually operable handles for each of the adjusting members, a leaf spring fixed to each of said adjusting cams and having 130

means to engage the adjusting cam with the corresponding disk for common movement, said springs when flexed disengaging the cam from the calculating disk and operatively engaging the corresponding handle, a rectilinearly movable plate having spaced slots in which the respective leaf springs are engaged, an operating crank handle for the disks and having a spring pressed bolt 5 silently projected when the crank handle and the calculating disks are in their zero positions, a longitudinally extending reciprocatable rod engaged and shifted in one direction by said bolt when the crank handle

is in its zero position, a yoke pivotally connected to the plate and pivotally mounted intermediate its ends, and a lever pivoted intermediate its ends and pivoted at one end to one end of said yoke and at its opposite end to the rod whereby to cause the shifting of the plate to flex the leaf springs and connect them to the handles when said rod is engaged by the bolt on the crank handle. 15

In testimony that I claim the foregoing as my invention, I have signed my name 20 25 hereunder.

HUGO ENDERS.
